UNITED STATES PATENT OFFICE.

EDWARD J. VOLK, OF CLEVELAND, OHIO.

COLLAPSIBLE TUBE.

1,296,884.

Specification of Letters Patent. Patented Mar. 11, 1919.

Application filed October 7, 1918. Serial No. 257,153.

To all whom it may concern:

Be it known that I, EDWARD J. VOLK, a citizen of the United States, residing at Cleveland, in the county of Cuyahoga and 5 State of Ohio, have invented certain new and useful Improvements in Collapsible Tubes, of which the following is a specification.

This invention relates to collapsible tubes 10 employed for such fluids as tooth paste, shaving cream, paint and the like, the material being discharged from the tube by compression of the body of the tube.

The object of the present invention is to 15 reduce the cost of the tube by omitting the screw cap ordinarily applied thereto and to provide means for preventing the discharge of the material after the desired quantity is ejected, which leads to unsanitary conditions.

These objects are effected by the use of one or more springs placed inside the neck of the tube and which act to close the discharge opening except when pressure is applied to 25 the tube.

The invention is illustrated in the accompanying drawings in which Figure 1 is a sectional view of one form of the device. Fig. 2 is a similar view of a modification. 30 Fig. 3 is a similar view of another modification. Fig. 4 is an end view of Fig. 1. Figs. 5 and 6 are details of one of the springs.

Referring specifically to the drawings, 6 indicates the body of the collapsible tube 35 and 7 the neck thereof, the latter being relatively rigid, and having an outlet slot 8 at the end.

As shown in Fig. 1, I place a pair of flat 40 spring plates 9 in the neck of the tube. Each plate has at its front end an offset part 10, and at its rear end has two lateral projections 11. The springs are set in the neck in such manner that they incline toward each other and meet just behind or within the 45 opening 8 at the mouth of the tube, and normally they press together so that the offset parts 10 close the opening 8. The springs are fastened in the tube by setting the lugs 11 in grooves indicated at 12 in the opposite 50 walls of the neck, and are frictionally held in the position described.

In the modification shown in Fig. 2 only 55 one spring 9^a is used, and it is bent sufficiently to normally extend across the bore of the neck, with the offset 10^a behind the discharge slot 8. In the form shown in

Fig. 3, the springs 9^b have no offsets at their front ends, but project in straight or parallel lines in contact into the mouth 8^a of the tube, as indicated at 10^b. 60

In all the forms, the springs are wide enough to normally close the mouth of the tube. When the tube is compressed, the pressure of the material forces the springs apart, in the forms shown in Figs. 1 and 3, 65 or forces aside the single spring shown in Fig. 2, thereby uncovering the slot 8 and permitting the material to escape through the same. When the pressure is released, the springs resume the normal position and prevent further escape or leakage of the material. The use of a cap is unnecessary although it may be applied if desired. 70

I claim:

1. A collapsible tube having a discharge 75 opening, and a spring plate located within the tube and extending across such opening and movable laterally by pressure of the material in the tube to uncover such opening.

2. A collapsible tube having a neck and 80 discharge outlet at the end thereof, of a spring plate fixed in the neck and projecting at an inclination adjacent to said opening, and movable laterally by pressure flow of the material through the neck to uncover 85 said outlet.

3. A collapsible tube having a relatively 90 rigid neck and a discharge outlet at the end thereof, and a spring fixed at its rear end in the neck and extending forwardly at an inclination toward said outlet, with its front end normally obstructing said outlet, the spring being yieldable laterally by pressure of the material in the tube to open said outlet. 95

4. A collapsible tube having an outlet at the front end thereof, and a flat spring cut-off fixed in the tube and projecting at an angle toward said outlet, and having an offset part at its front end which normally 100 closes said outlet, the spring being movable laterally by pressure flow of the material in the tube to uncover and open said outlet.

5. A collapsible tube having a discharge 105 passage leading to an outlet at the front end thereof and a pair of flat springs which converge in said passage toward said outlet and meet at their front ends adjacent the outlet to close the same, the springs being yieldable laterally to separate their ends and open the 110 outlet.

6. A collapsible tube having a neck and an

outlet at the front end thereof, and a pair of converging spring plates fixed at their rear ends to the neck and having offsets at their front ends adapted to normally close the outlet, said springs being yieldable laterally by pressure of material in the tube to open the outlet.

In testimony whereof, I do affix my signature in presence of two witnesses.

EDWARD J. VOLK.
